UNITED STATES PATENT OFFICE

LOUI LOUIS, OF MONTICELLO, NEW YORK

COLLAR SUPPORT AND NECKTIE HOLDER

Application filed April 14, 1931. Serial No. 530,006.

This invention relates to a collar support and necktie holder and in particular to a device which is used in connection with both the collar and the tie to enhance their combined 5 appearance.

A particular object of my invention is to provide a collar support which may be employed with either the knot type tie or the bow tie, the purpose of the support being to hold the extended collar points flat and prevent curling of the same.

A further object of my invention is to provide a device which may be placed over the collar button and within the collar that is either fastened to or forms a part of a shirt, the device having extended arms for the purpose of engaging the under side of the collar points to maintain the same in shape, my invention being further applicable to a bow tie construction to form a part thereof in which event, the device becomes a necktie holder.

Changes and variations may be made in the construction shown and described without departing from the principles of the invention 25 or sacrificing its chief advantages; hence such invention is not to be confined to the structures shown in the accompanying drawings.

Figure 1 is a view in front elevation of a collar and tie combination to which has been applied my improved collar support and necktie holder.

Figure 2 is a view in front elevation of the collar support and necktie holder.

Figure 3 is an enlarged section taken on the line 3—3 of Figure 1 and shows the method of holding the collar point or tip in extended, uncurled position through the medium of my device.

Figure 4 is an enlarged section taken on the line 4—4 of Figure 2 and shows the collar engaging loop and method of connecting the same to the wing plate of my device, and

Figure 5 is a view in elevation of the rear side of a bow tie, the holding member of which constitutes a portion of my improved collar support and necktie holder.

Referring to the drawings in detail and in particular to Figures 1 to 4 inclusive, 5 indicates a collar and 6 a shirt which are secured together in the well known manner

and through the medium of a suitable button 7 where the collar is detachable from the shirt. The button 7, of course, is employed to hold the ends of the collar closed and the illustration of my invention is thus carried out in connection with a collar having extended points 8 beneath which is disposed the knot 9 of the tie 10.

It has always been a problem to keep the points 8 of the collar flat against the shirt and to prevent the same from curling up and in order to do this, use has been made of bar pins, stiffening members inserted in the collar and other devices which have proven unsatisfactory or hard to adjust. In carrying out my invention, I employ a wing plate 11 to the ends of which are pivotally secured as at 12, the depending arms 13 which carry on their front face and adjacent their lower ends, the piercing elements or pins 14, the same being secured to the arms in any suitable manner. The center 15 of the wing plate has secured thereto, the bent wire loop or eye 16, the looped portion 17 thereof being arranged to snap over the button 7 employed in holding the ends of the collar together so that the wing plate 11 may be secured in position preparatory to the tying of the tie thereover, as illustrated in Figure 1. The tie 10 is then knotted and forced up into position and further secures the wing plate from movement. The arms 13 are then adjusted pivotally so that they lie behind the extended points 8 of the collar 5 and a slight pull down on the points of the collar and forcing them against the ends of the arms 13 causes the pins 14 in the arms 13 to engage the material of the collar on the under side of the points 8 as illustrated in Figure 3 to effectively hold the collar points in their extended position and prevent the same from rolling.

My collar support and necktie holder is preferably made of very thin metal although it can be made of any rigid material that is light and durable and will not soil the collar or tie.

As a modified form of my invention, I may incorporate my improved collar support and necktie holder with a bow tie and as illustrat-

ed in Figure 5, the wing plate 11 is covered with a suitable fabric 18 matching the tie material, which wing plate is then secured in position against the tie 19 through the medium of the tie binding strip or center piece 20, it being understood that the bow tie in present day use has a back piece corresponding to the wing plate 11 as illustrated in Figure 5, this piece being positioned beneath the collar 10 while the bow of the tie 19 is outside the collar. After the wing plate 11 is positioned on the tie, the arms 21, which are similar to the arms 13 in the construction shown in Figure 2, are secured to the outer end of the wing 15 plate 11 so that they can have free pivotal movement and when not in use may be folded up adjacent the button catch loop 22 which is secured to the tie binding strip in any suitable manner or secured directly to the wing 20 plate 7 through the tie binding strip or center piece 20.

The arms 20 carry at their lower ends, the pins 23 which are arranged to engage the material of the under side of the collar points 25 8 to hold the same in their extended position and prevent a curling thereof.

It is evident, therefore, that I have provided a collar support and necktie holder which may be employed in connection with a 30 tie of the knot type or with a bow tie to hold the collar points in their extended position to prevent rolling or curling thereof which detracts from the appearance of the wearer.

As illustrated in Figure 5, my improved 35 invention forms a part of the tie and consequently becomes a necktie holder in that the bow tie is mounted thereon and the extended arms 21 also retain the points of the collar in their extended position and prevent curling 40 thereof.

My invention is not to be restricted to the precise details of construction shown since various changes and modifications may be 45 made therein without departing from the scope of the invention or sacrificing the advantages derived from its use.

What I claim is:—

1. A collar support comprising a wing 50 plate, a button engaging means for supporting the plate in position, arms pivoted to and extending from the plate, and means on the ends of the arms for engaging the points of the collar.

55 2. A collar support comprising a wing plate, a button engaging means for supporting the plate in position, arms pivoted to and extending from the ends of the plate and piercing members on the ends of the arms 60 for engaging the extended tips of a collar.

3. A combination collar support and tie 65 holder comprising a wing plate constituting a part of a tie, a button engaging means for supporting the plate in position, arms pivoted to and extending from the ends of the

plate, and piercing members on the ends of the arms for engaging the extended tips of a collar.

In testimony whereof I affix my signature.
